(57) **CLAIM**

The ornamental design for a waterpark float, as shown and described.

DESCRIPTION

FIG. 1 is a front perspective view of the waterpark float.

FIG. 2 is a top view of the waterpark float.

FIG. 3 is a bottom view of the waterpark float.

FIG. 4 is a side view of the waterpark float.

FIG. 5 is another side view of the waterpark float.

FIG. 6 is a front view of the waterpark float; and,

FIG. 7 is a rear view of the waterpark float.

The broken lines depict portions of the article that form no part of the claimed design.
